Primary Examiner — Cynthia M Chin*(74) Attorney, Agent, or Firm* — Sughrue Mion, PLLCCLAIM

The ornamental design for a set of cookware pot handles, as shown and described.

DESCRIPTION

FIG. 1 is an isometric perspective view of set of cookware pot handles showing my new design;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a cross-section view thereof taken through line 8-8 of FIG. 6.

The broken lines depict environmental subject matter only and form no part of the claimed design.
